COFFEE MAKER

William M. Day, 11 Hatters Lane, Farmington, Conn.

Filed Nov. 9, 1960, Ser. No. 62,788

Term of patent 7 years

(Cl. D44—26)

FIG. 2

FIG. 1

FIG. 4

FIG. 3

FIG. 1 is an elevational view of one side of the coffee maker embodying my design;

FIG. 2 is a rear elevational view, showing the handle;

FIG. 3 is a front elevational view, showing the spout; and

FIG. 4 is a top plan view thereof.

The dominant features of my design reside in the full-line portions of the drawing.

I claim:

The ornamental design for a coffee maker, as shown and described.
